COMPRESSOR FOR FLUID PRESSURE SYSTEMS

Wallace F. Oliver, Detroit, Mich., assignor to
Hydraulic Brake Company, Detroit, Mich., a
corporation of California

Application October 31, 1934, Serial No. 750,783

3 Claims. (Cl. 60—54.6)

This invention relates to fluid pressure systems, and more particularly to compressors for fluid pressure systems.

In fluid pressure systems including compensating compressors, the compression piston has a plurality of passages in its head providing communication between a chamber back of the piston head and that portion of the cylinder forward of the piston head.

10 These passages are controlled by a collapsible leak-proof cup which functions to close the passages on the forward stroke of the piston and to provide for free flow of fluid through the passages on the retraction stroke of the piston.

15 Generally these cups have given satisfaction. However, after long usage the cups become deformed, and the material from which the cups are made is forced into the passages. This causes serious damage to the cups and inhibits the 20 free flow of fluid through the passages during the retraction stroke of the piston. The present invention aims to overcome this objection.

An object of the invention is to provide a compression piston having a concentric extension on 25 its head and spaced apertures in the head around the extension of relatively shallow depth and a leak-proof cup supported on the extension so that no portion of the cup may enter the apertures in the head.

30 Another object of the invention is to provide a cup having a rigid bottom and a flexible wall.

Another object of the invention is to provide a collapsible leak-proof cup provided with a non-flexible bottom and flexible side walls.

35 Yet a further object of the invention is to provide a leak-proof cup having a rigid bottom and flexible side walls provided with grooves or channels arranged to enhance the flexibility of the wall of the cup and to provide for the free passage 40 of fluid upon collapse of the cup.

Other objects of the invention will appear from the following description taken in connection with the drawing which forms a part of this specification, and in which,—

45 Figure 1 is a side elevation, partly in section, of a compressor embodying the invention;

Figure 2 is a sectional view of the cup;

Figure 3 is a bottom plan view of the cup; and
Figure 4 is a side elevation of the cup.

50 Referring to the drawing for more specific details of the invention, 10 represents a fluid reservoir having a cylinder 12 at its base. The cylinder is closed at one end as by a head and is open at its other end, and spaced ports 14 and 55 16 arranged in the wall of the cylinder provide

communications between the cylinder and the reservoir. The cylinder also has a discharge port 18 in its head, which may be connected to fluid pressure motors of any preferred type for the actuation of various instrumentalities. 5

A piston 20 reciprocable in the cylinder is held against displacement by a retaining ring 22 seated in a circumferential groove in the wall of the cylinder adjacent the open end of the cylinder. The piston has a reduced body portion 24 providing in conjunction with the wall of the cylinder an annular chamber 26 communicating with the reservoir 10 by way of the port 14, and a leak-proof cup 28 fitted in a circumferential groove in the skirt of the piston inhibits the passage of 15 fluid from the open end of the cylinder. The head of the piston has a concentric extension 30 of slight depth, and a plurality of apertures or passages 32 arranged in spaced relation to one another around the extension. These apertures provide communications between the annular chamber 26 and that portion of the cylinder 20 forward of the head of the piston.

A check valve 34 seated on the head of the cylinder controls the discharge port 18, and a 25 collapsible leak-proof cup 36 on the extension 30 of the piston head inhibits the flow of fluid past the piston on its compression stroke and provides for free flow of fluid from the annular chamber 26 to that portion of the cylinder forward of the 30 piston head on the retraction stroke of the piston. A spring 38 interposed between the check valve 34 and the leak-proof cup 36 retains the valve 34 and collapsible leak-proof cup 36 against displacement and also serves to return the piston 35 to its retracted position.

Heretofore some difficulty has been experienced by reason of deformation of the collapsible leak-proof cup due to usage, resulting in the material from which the cup is made being forced into the 40 apertures or passages 32 in the head of the piston. This results in serious injury to the cup and interrupts the flow of fluid through the passages on the return or retraction stroke of the piston. To overcome this difficulty, the cup 36 45 is provided with a metallic bottom 40 including a disk having its periphery turned as indicated at 42, and a rubber ring or wall 44 is moulded on the periphery of the disk. Preferably the wall of the cup tapers gradually outward from the 50 periphery of the disk to the rim of the cup, and the wall is provided with a plurality of spaced longitudinal grooves 46 communicating with a centrally disposed circumferential groove 48. These grooves lend flexibility to the wall of the 55

cup and provide for free flow of fluid past the cup when collapsed.

In practice, during the compression stroke of the piston, the metallic portion of the cup seats 5 on the extension 30 of the piston head and inhibits the rubber portion of the cup from contacting with the head of the piston, thus rendering it impossible to cause damage to the cup or clog the passages 32 in the piston head.

10 Although I have shown and described a specific embodiment of the invention I am fully aware that many modifications thereof are possible. Therefore the invention is not to be restricted except in so far as is necessitated by the 15 prior art and by the scope of the appended claims.

Having thus described the various features of the invention, what I claim as new and desire to secure by Letters Patent is,—

1. A compressor for a fluid pressure system 20 comprising a cylinder, a piston reciprocable in said cylinder, said piston having a forwardly projecting tubular extension and passages through said piston radially outward of said extension, and a packing cup for said piston, said packing cup having a metallic bottom adapted to seat on 25 said extension, said bottom extending across the adjacent ends of said passages in spaced relation thereto, said packing cup including a rubber flange molded to said bottom and extending forwardly of said piston.
2. A compressor for a fluid pressure system of 30 the class described, comprising a cylinder, a pis-

ton reciprocable therein, said piston having a tubular extension projecting forwardly therefrom and passages through said piston located radially outward of said extension, and a packing cup associated with said piston, said packing cup having a metallic bottom adapted to seat on the extension, said bottom extending across the adjacent ends of said passages but spaced from the wall of said cylinder, said packing cup also including a flexible wall attached to said bottom 10 and bridging the gap between said bottom and said cylinder wall, said flexible wall being adapted to seal against said cylinder wall during forward movement of said piston to prevent flow of fluid therewith but flexing inwardly during reverse 15 movement of said piston to prevent flow of fluid therewith.

3. In a compressor for a fluid pressure system, the combination of a cylinder, a piston reciprocable therein, a reservoir communicating with 20 the rear of said piston, said piston having passages therethrough and a packing cup associated with said piston, said packing cup including an imperforate metallic bottom contacting said piston, and a flexible wall attached to said bottom 25 in spaced relation to said passages, said flexible wall sealing against said cylinder during forward movement of said piston and flexing away from said cylinder during reverse movement of said piston. 30
